SUCTION CLEANER

Filed Nov. 22, 1928

Inventor:
Andrew Howard Ryan,
By Harry S. Daniels
Atty.

UNITED STATES PATENT OFFICE

ANDREW HOWARD RYAN, OF CHICAGO, ILLINOIS, ASSIGNOR TO THE HOOVER COMPANY, A CORPORATION OF OHIO

SUCTION CLEANER

Application filed November 22, 1928. Serial No. 321,050.

This invention relates to dust bags for suction cleaners and particularly to means for completely and adequately expelling the refuse collected in the bag.

5 Bags for suction cleaners are usually and preferably made from a rough cloth material, having a nap, which permits the air forced from the cleaner to readily pass through the bag and at the same time holds the dust inside and prevents it from seeping through the bag. During operation of the cleaner particles of thread, hair, carpet nap, and other particles become matted inside of the bag making it difficult to remove the same thoroughly when the bag is being cleaned. Ordinarily the bag must be violently shaken and often it is necessary to insert one's hand or a tool of some kind into the bag to remove this matty refuse.

20 The present invention overcomes these disadvantages by providing means for beating or otherwise agitating the bag to remove the dust and other refuse which clings to the inside and for forcing the refuse through the bag opening so that all the dirt can be readily expelled without inserting one's hand or a tool.

The object of the invention is to provide simple and novel means which is secured to 30 the inside of the bag for assisting in removing the dirt which has become collected therein.

Another object is to provide an element which is swingingly attached to the inside of 35 the bag to assist in forcing masses of accumulated dirt through the orifices in the bag ring when the bag is being emptied, and also to assist in beating dirt from the walls of the bag.

40 Other objects and advantages will herein-after appear.

In the accompanying drawing, which illustrates a selected embodiment of the invention, the views are as follows:

45 Fig. 1 is a perspective view of a suction cleaner embodying the invention.

Fig. 2 is a detail elevation of a dust bag partly in section and having the invention applied thereto.

50 Referring to the drawing, 5 designates a

suction cleaner generally and to which a dust bag 6 is operatively connected.

A rod 7 which may be made of rattan, aluminum or any other suitable substance is arranged inside of the bag 6. A fastening member 8 which may be made of cloth or other flexible material is secured to the top of the bag at 9 and is fastened to the rod at 10, for maintaining the rod in proper position relative to the bag.

The operation of the device is as follows: When it is desired to clean the bag to remove the refuse contained therein, the bag is removed from the suction cleaner and held in an upright position with the opening 11 in 65 the ring 12 facing downwardly. As the bag is flexible and collapsible the upper end of the rod may be easily manipulated from the outside of the bag at the point 9 and operated to beat the inside walls thereof to remove 70 all particles of dust and other refuse which may cling to the bag. After sufficient beating, the dust which was collected on the inside of the bag will fall to the lower end thereof, and by poking the rod 7 through the 75 opening 11 in the bag ring 12 all the plugs, cakes and matted particles of dirt may be readily forced through the opening in the bag ring without necessitating one's hands coming in contact therewith.

80 The invention provides means of simple and novel construction for agitating the bag, and for forcing the refuse in the bag through the orifice in the bag ring. The rod 7 being positioned entirely within the bag and of 85 relatively light weight disturbs in no way the normal operation of the machine.

The invention is susceptible to various modifications and adaptations without departing from the spirit or scope of the invention as set forth in the claims.

85 The invention is hereby claimed as follows:

1. A suction cleaner comprising a dust bag having open and closed ends, means arranged entirely within said bag and adapted 95 to be operated from the closed end thereof for agitating said bag to remove the dust therefrom.

2. A suction cleaner comprising a dust bag, a bag ring connected to said dust bag for de- 100

tachably securing the same to the cleaner, and a rod located entirely within said bag and flexibly connected to the upper part thereof to assist in forcing the refuse in said bag through an orifice in the bag ring and for beating the dirt from the walls of said bag.

5 3. A dust bag for suction cleaners having rigid means arranged entirely within said bag for forcing the refuse contained in said bag out of the open end thereof.

10 4. In a dust bag adapted to be connected to a suction cleaner, a bag of collapsible material having an open and a closed end and means carried entirely within said bag and swingingly mounted at the closed end thereof to beat said bag and dislodge the foreign matter therefrom.

15 5. In a dust bag adapted to be connected to a suction cleaner, a bag of collapsible material having an open and a closed end and means carried entirely within said bag and swingingly mounted at the closed end thereof to beat said bag and dislodge the foreign matter therefrom, said means comprising a rigid rod.

20 25 Signed at Chicago, in the county of Cook and State of Illinois, this 20th day of November, A. D., 1928.

ANDREW HOWARD RYAN.
